UNITED STATES PATENT OFFICE.

JOHN F. SELMEIER, OF NORWOOD, OHIO, ASSIGNOR TO PECK, SELMEIER & PECK, OF CINCINNATI, OHIO.

DESIGN FOR A RING.

SPECIFICATION forming part of Design No. 35,163; dated October 8, 1901.

Application filed August 26, 1901. Serial No. 73,406. Term of patent 7 years.

To all whom it may concern:

Be it known that I, JOHN F. SELMEIER, a citizen of the United States, residing at Norwood, in the county of Hamilton and State of Ohio, have invented and produced a new and original Design for a Ring, of which the following is a specification, reference being had to the accompanying drawings, forming part thereof.

10 Figure 1 is a side elevation of a ring, showing my new design. Fig. 2 is an end elevation of the same. Fig. 3 is a view in perspective of the same. Fig. 4 is a plan view of the same.

15 As shown in the drawings, the leading or material feature of my design consists in the representation of a plurality of two-headed eagles, sometimes called "double" eagles, in such position as to be adjacent to the position 20 for the diamond, gem, or jewel, with one of the outstretched wings of each of two neighboring two-headed eagles taking between the heads of the two eagles. At each side of the ring-setting A, toward the ring-band B, there 25 is a representation of a two-headed eagle C,

each of whose heads D is in such position as to be adjacent to the position for the diamond, gem, or jewel, which latter position is in the ring-setting. One of the outstretched wings E of each of two neighboring two-headed eagles is stretched upwardly between the heads of the two eagles. The order of succession of heads and wings is two heads of a two-headed eagle, one wing of each of two two-headed eagles, followed by the two heads of another two-headed eagle, continuing in the order named.

Having described my invention, what I claim as new, and desire to secure by Letters Patent, is—

40 The design for a ring, substantially as shown and described.

In testimony whereof I have signed my name hereto in the presence of two subscribing witnesses.

JOHN F. SELMEIER.
